UNITED STATES PATENT OFFICE.

JOHN A. JOHNSON, OF MERIDEN, CONNECTICUT, ASSIGNOR TO THE M. B. SCHENCK COMPANY, OF MERIDEN, CONNECTICUT, A CORPORATION OF CONNECTICUT.

LOCK-LEVER CASTER.

1,137,329.

Specification of Letters Patent. Patented Apr. 27, 1915.

Application filed February 15, 1915. Serial No. 8,208.

To all whom it may concern:

Be it known that I, JOHN A. JOHNSON, a citizen of the United States, residing at the city of Meriden, county of New Haven, State of Connecticut, have invented certain new and useful Improvements in Lock-Lever Casters; and I do declare the following to be a full, clear, and exact description of the invention, such as will enable others skilled in the art to which it appertains to make and use the same.

My invention relates to brakes for casters, and has for its object to hold the caster roller firmly as against rotation, and to restore the parts to normal condition so that the roller will be free to rotate; and furthermore to effect these results without employing any spring action to the parts and by causing the locking element to bind in its locked position firmly and flatly against the caster roller.

With these ends in view my invention consists in the construction and arrangement of parts hereinafter fully described and more particularly set forth in the appended claims.

My invention may be embodied in several forms all of which in substance are mechanically the same, and I have therefore shown and will hereinafter describe these forms.

In the accompanying drawing Figure 1 is a side elevation, partly broken, of one form of my improvement with the parts in unlocked condition. Fig. 2 is likewise a side elevation of the structure shown at Fig. 1, partly broken, and showing the position of the parts in locked condition. Fig. 3 is a section at the line 3—3 of Fig. 2. Fig. 4 is an elevation similar to Fig. 2 except that in Fig. 2 the pivot of the lock lever is a stud extending inwardly from one horn of the caster while in Fig. 4 this pivotal connection is formed by a stud extending from the lock lever into a perforation in one horn of the caster. Fig. 5 is a perspective view of the lock lever utilized in the construction shown at Fig. 4. Fig. 6 is a view similar to Fig. 4, except that it shows a pivotal point for the lock lever consisting of a lip outwardly extending from the latter within a perforation in one horn of the caster. Fig. 7

is a perspective view of the lock lever utilized in the construction shown at Fig. 6. Fig. 8 is a view similar to Fig. 6 except that the cam teat extends inwardly from one horn of the caster and normally engages a perforation in the lock lever when the parts are in unlocked position, while in locking position this teat is forced outside of said perforation against the lock lever. Fig. 9 is a section at the line 9—9 of Fig. 8. Fig. 10 is a section at the line 10—10 of Fig. 8, but showing the parts in normal condition with the cam teat extending within the perforation in the lock lever, and Fig. 11 is a perspective view of the form of lock lever utilized in the structure shown at Figs. 8, 9, and 10.

Similar numerals of reference denote like parts in the several figures of the drawing.

A peculiarity of my invention, in all its forms, is that the lock lever is pivotally connected to one horn of the caster eccentric of the pintle of the caster roller and between said horn and roller, and that not only has this lever a free rocking movement around its pivot but also a sliding movement lengthwise of the pivotal connection. Also, in all forms of my improvement, the locking is effected by means of interengaging surfaces carried by the lever and the inner face of the horn member, and in all instances these surfaces engage with a cam action which forces the broad surface of the lock lever firmly and flatly against the adjacent side of the caster roller so as to bind the latter firmly throughout an extended area. Also, in all forms of my improvement shown, no special stops are required to limit the rocking movements of the lock lever, since, in all instances, the movement of this lever to free the caster roller is limited by the abutment of the upper part of the lever against the bridge frame, while the movement of such lever to lock the caster roller is limited by the abutment of the lower edge of the lever against the pintle of the roller.

Referring particularly to Figs. 1, 2 and 3, of the drawing, 1, 2, are the usual parallel and spaced horns of the caster frame, 3 the bridge at the top which connects these horns from which bridge the stem 4 of the caster

extends upwardly, and 5 is the caster roller pivoted between the horns 1, 2, near the lower end thereof, by means of the pintle 6, all of which parts when properly assembled 5 as shown constitute the usual form of caster.

In adapting my improvement to a caster, I utilize a lock lever which comprises a plate 7 which is vertically disposed in the assembled structure the lower extremities 10 of this plate being formed with rectangular extending step-like portions 8, 9, for convenience in manipulating the lock lever as will be more fully explained.

Extending inwardly from the horn 1 and 15 eccentric of the pintle 6 is a stud 10 which latter projects through a circular perforation 11 in the plate 7 whereby a pivotal point for the lock lever is afforded.

12 is a teat carried by the plate 7 and extending beyond the surface thereof toward the horn member 1 this teat being preferably forced from the stock of the plate as shown.

By placing the foot upon the step 8 and 25 forcing the latter downwardly the lock lever will be swung to the position shown at Fig. 2 and during the course of this swinging movement the teat 12 will cam against the inner face of the horn 1 and thereby force the lock lever throughout its entire broad area against the side surface of the roller 5, thus locking the latter against rotation, and in this connection it will be observed that the lock lever does not impinge against 30 the roller at a mere point or throughout a comparatively small area of the side face of the roller, but that, owing to the fact that the pivotal relation of the lock lever is such that it can slide freely along such pivotal point, substantially the entire area of the lock lever is bound against a very substantial area of the side surface of the roller.

When the parts are in the position shown at Fig. 1, to which position they have been 45 brought by pressure against the step 9, it will be observed that the top edge of the plate 7 is in abutment against the bridge 3 of the caster, thus affording a stop; and it will be observed by reference to Fig. 2 that, 50 when the parts are in locked condition, the lower edge of the plate 7 will be in abutment against the pintle of the caster, thus likewise affording a stop engagement.

Referring to Figs. 4 and 5, instead of the 55 stud projecting from the inner face of the horn 1 through a perforation in the plate 7, a similar stud 13 extends from the plate 7 within a perforation 14 in the horn 1, and this stud 13 may be formed from the 60 plate 7 by a drawing operation or it may be secured thereto in any suitable manner.

Referring to Figs. 6 and 7, I have shown a pivotal structure of the same character as that shown at Figs. 4 and 5 except that a lip

15 of the proper dimensions is cut from the 65 stock of the plate 7 and is extended at right angles thereto so as to form a pivotal stud which extends through the perforation 14. In other words, this stud 15 performs the same function as the stud 13 the only difference being that it is not circular in cross section.

The structures which have been described all contemplate the provision of the cam teat as a part of the lock lever, and when the 75 parts are in unlocked positions this teat projects outwardly beyond the inner face of the horn member 1, but, of course, such teat portion may extend from the inner face of the horn member itself so that when the 80 lever is operated such teat may exert a camming action against the lever to force the same into locking contact with the face of the caster roller, and accordingly, referring to Figs. 8, 9, 10, and 11, I have shown a 85 teat 16 extending from the inner face of the horn member 1, and preferably formed by forcing the stock of said member inwardly, and in normal or unlocked position this teat extends within a perforation 17 in the lock 90 lever, as more particularly shown at Fig. 10, and when the latter is operated to perform its function of locking the caster roller, this perforation 17 will be forced clear of the teat 16 and the latter will cam against the 95 outer face of the plate 7 of the lever so as to force the latter, in the manner hereinbefore described, firmly against the side face of such roller, as more particularly shown at Fig. 9.

100

From the above description it will be clear that the essential features of my improvement comprise the arrangement of the locking lever between the horn and caster roller, the sliding pivotal connection between said 105 lever and the adjacent horn of the caster and eccentric of the pintle of the roller itself, and finally the engagement of surfaces, carried by the horn member and lock lever, with a cam-like action, whereby the broad area 110 of the lock lever is firmly impinged against a substantial area of the side face of the caster roller, all of which features are embodied in and form a characteristic of the various structures illustrated and hereinbefore described. Further it will be noted that I do not employ any spring feature, whatsover, nor do I rely on the resiliency of any part of my structure in effecting the result aimed at.

115

While I prefer to provide for pivotal connection between the lock lever and horn member that is eccentric of the axis of the pintle that passes through the caster roller, nevertheless it is fully within my invention 125 to pivot said lever around said pintle, because the cam action of the surfaces carried by the lever and horn would be precisely the

120

same as in the structures hereinbefore described, and I therefore do not wish my invention limited in this respect.

What I claim as new is:—

1. A lock lever caster, comprising spaced horn members, a caster roller, a pin extending through said members and roller whereby the latter is journaled, and a brake lever interposed between one of the horn members and the roller and pivoted to said horn member eccentric to said pin.
2. A lock lever caster, comprising spaced horn members, a caster roller, a pin extending through said members and roller whereby the latter is journaled, and a pivoted brake lever interposed between one of the horn members and the roller and having a lateral projection adapted to be forced against said horn member to bind said lever firmly against the side face of the roller thereby locking the latter.
3. A lock lever caster, comprising spaced horn members, a caster roller, a pin extending through said members and roller whereby the latter is journaled, and a brake lever pivotally connected to the inner face of one of said horn members and capable of lateral movement, said lever and horn member having interengaging means for causing the lever to be forced firmly against the side of

the roller when said lever is swung to locking position.

4. A lock lever caster, comprising spaced horn members, a caster roller, a pin extending through said members and roller whereby the latter is journaled, and a brake lever between one of the horn members and the roller, said lever and horn member having a pivotal relation eccentric to said pin and also having interengaging cam surfaces, whereby when the lever is in unlocked position the roller is free to rotate, but when said lever is swung to locked position it will be forced firmly against the side face of the roller to lock the latter as against rotation.

5. A lock lever caster, comprising spaced horn members, a caster roller, a pin extending through said members and roller whereby the latter is journaled, and a brake lever pivoted to the inner face of one horn member eccentric to said pin and having its locking and unlocking movements limited by said pin and by the caster frame.

In testimony whereof I affix my signature in presence of two witnesses.

JOHN A. JOHNSON.
